[57] CLAIM

The ornamental design for a computer stand with sliding keyboard shelf, as shown and described.

DESCRIPTION

FIG. 1 is a perspective view of a computer stand with sliding keyboard shelf showing my new design;
FIG. 2 is a right-side elevational view thereof;
FIG. 3 is a bottom plan view thereof;
FIG. 4 is a front elevational view thereof;
FIG. 5 is a rear elevational view thereof;
FIG. 6 is a perspective view thereof, the keyboard shelf shown extended from the front side;
FIG. 7 is a right side elevational view thereof;
FIG. 8 is a perspective view thereof, the keyboard shelf shown extended from the rear side;
FIG. 9 is a left side elevational view thereof;
FIG. 10 is a rear elevational view thereof, the keyboard shelf shown extended from the rear side; and,
FIG. 11 is a front elevational view thereof, the keyboard shelf shown extended from the rear side.

Fig. 1.**Fig. 2.****Fig. 3.**

Fig. 6.**Fig. 7.****Fig. 4.****Fig. 5.**

Fig. 8.**Fig. 9.****Fig. 10.****Fig. 11.**
